UNITED STATES PATENT OFFICE.

JAMES F. McELROY, OF ALBANY, NEW YORK, ASSIGNOR TO CONSOLIDATED CAR HEATING COMPANY, A CORPORATION OF WEST VIRGINIA.

PRESSURE-MOTOR.

1,072,749.

Specification of Letters Patent. Patented Sept. 9, 1913.

Application filed November 8, 1910. Serial No. 591,210.

To all whom it may concern:

Be it known that I, JAMES F. McELROY, a citizen of the United States, residing at Albany, county of Albany, State of New York, have invented certain new and useful Improvements in Pressure-Motors, the following being a full, clear, and exact disclosure of the one form of my invention which I at present deem preferable.

10 For a detailed description of the present form of my invention, reference may be had to the following specification and the accompanying drawings forming a part thereof, in which—

15 Figures 1 and 2 are plan views partly in section; Fig. 3 is a vertical section with the supply pipes turned at right angles to bring them in view; Figs. 4 and 5 are respectively a plan and side view on a large scale, showing a different mode of support and also the electric contacts; Figs. 6 to 10 inclusive show details, and Fig. 11 is a general diagram, showing the piping and door connection.

25 My invention relates to a pressure motor particularly designed for the operation of a door and includes an arrangement of parallel and opposed cylinders in which are both motive power and also dampening, cushioning or retarding means. Preferably I use four such cylinders, in two sets, the sets being both mounted in a central casting but out of line one with the other. In each

30 set is a power cylinder and a cushioning cylinder and both piston rods, in either set, are connected to a crosshead which travels on the opposite set. The two crossheads are connected by a rod so that they move in unison. By this means the motor includes a

35 power cylinder for each direction of movement of the door and also a cushioning cylinder for each power cylinder, the cushioning cylinder in one set serving to cushion the movement produced by the power cylinder in the opposite set. The pistons are open at their inner ends so that no stuffing boxes are required, and the several piston rods are loosely connected to their respective pistons and crossheads to avoid strains.

40 At each end of the apparatus is an inlet connection for the power cylinder and a check valve for the cushioning cylinder. In Fig. 1, A¹ A² represent the two cylinders composing one of the aforesaid sets,

45 and B¹ B² are the corresponding cylinders

forming the other set. Both sets of cylinders are secured at their inner ends to a central standard X, the set at the right being on a lower level than the set at the left and the two sets are thereby offset with respect to each other. The cylinders A¹ and B¹ are power cylinders provided at their outer ends with a pipe connection from the source of supply, while A² and B² are cushioning cylinders provided at their outer ends with check valves and constricted outlets. The cylinders A¹ and A² are each provided with a piston and with piston rods a¹ a² connected thereto. The opposite ends of these rods a¹ a² are also loosely connected to a crosshead D² which travels on the outside of the opposite set of cylinders B¹ B² which therefore form a slideway for the crosshead D². Similarly, cylinders B¹ B² are provided with pistons and with piston rods b¹ b² therefor and they are connected in like manner to the crosshead D¹ which travels upon the set of cylinders A¹ A² which serve as slideways therefor. The supply pipes, connected at the outer ends of the power cylinders A¹ B¹, are controlled by a reversing valve V whereby air pressure may be admitted to one cylinder and exhausted from the other. This valve forms no part of my present invention, being claimed in a previous application for patent, Ser. No. 477,868, filed February 15th, 1909.

50 The check valves at the outer ends of the cushioning cylinders A² and B² and the details of their arrangement are shown in Figs. 8, 9 and 10. A plug F² is shown in these figures (a similar plug F¹ being provided for the cylinder A²) and is adapted to be screwed into the end of the cylinder B² and project a considerable distance into the tube to reduce the clearance as compared with the clearance in the power cylinders A¹ B¹. The plug F² is provided with two longitudinal perforations or ducts, the upper and smaller one, f¹, communicating with an outlet passage f² and controlled by an adjusting screw f⁴ which carries at its inner extremity a taper plug which may be screwed into or out of the duct f¹ to adjust its capacity. The other perforation or duct f¹ is larger than f² and located below it. It communicates with the chamber f⁵ in which is an inwardly opening check valve f⁶. It will be understood that as the piston in the cushioned cylinder moves inward away

from its outer end, it will suck in air through the check valve f^6 and this air by a return movement of the piston will be forced out through the duct f^1 and its restricted opening in such a manner as to give a smooth cushioning or retarding effect on the movement of the piston in the corresponding power cylinder.

Figs. 6 and 7 show in detail the central casting of Figs. 1, 2 and 3. The two upper openings (see Fig. 7) in this casting K receive the ends of cylinders A^1 A^2 and the two lower openings receive the ends of the opposite set of cylinders B^1 B^2 . The central opening receives loosely the rod C which connects the crossheads D^1 and D^2 and causes them to move in unison. The connecting rod C and also the piston rods are detachably joined to the crossheads in any suitable or preferred manner. Figs. 6 and 7 also show a lubricating arrangement, there being cast in the central standard K two oil or grease cups k^1 k^2 communicating with a groove k^3 in the interior of each cylinder opening. The pistons are each provided with a circumferential groove G^1 which, in the extreme position of the piston, comes opposite the aforesaid groove k^3 as is shown clearly in Fig. 2. The oil or grease cups k^1 k^2 will each be closed by a screw plug (see k^4 , Fig. 5) which may be screwed in to force the grease into the aforesaid groove k^3 and the corresponding piston groove. In this way the piston will carry a supply of grease in its groove which will lubricate the interior of the cylinder.

In Figs. 4 and 5 the apparatus is shown as supported from beneath by three brackets O^1 O^2 and O^3 , whereas in Figs. 1, 2 and 3 it is arranged to be supported against a side wall by brackets k^5 shown in Fig. 7. I also show in Figs. 4 and 5 an electric contact intended to be operated by the motor itself in connection with a system of signals shown in my previous application for patent Ser. No. 539,536, filed Jan. 22, 1910. The purpose of the electrical contact is to close the signal circuit when the door reaches the end of its run and is closed as outlined in the said application. The crosshead D^1 carries a contact d , wedge-shaped at each end, adapted to enter between two springs d^1 , d^2 mounted on the central standard K by suitable insulating supports. Said springs serve as electrical contacts and are connected with the signal system above referred to, the circuit being closed when the contact d engages the springs. The two springs and the supports therefor are contained in a box or inclosure d^2 screwed upon the top side of the support K and provided with a spring-hinged cover which may be readily lifted for purposes of inspection. This cover is shown in place in Fig. 5 and removed in Fig. 4.

A motor constructed as above described may be connected to the door E, which is to be operated, by a link G. The link G is pivoted to the door at one end and at the other end to the crosshead D^1 as particularly appears in Fig. 11. In operation the compressed air will be admitted by the valve V to the outer end of one of the power cylinders—say cylinder A^1 . The piston in cylinder A^1 will thereby be forced toward the central standard and will at the same time force inward the piston of the cushioning cylinder B^2 which exerts its described retarding or cushioning effect. At the same time the air will be exhausted in the power cylinder B^1 which is connected to the atmosphere, while the cushioning cylinder A^2 will be taking its charge of air through the check valve f^6 . This will give the door a horizontal sliding movement in one direction, while, by reversing valve V, it will be similarly moved in the opposite direction by the corresponding action of power cylinder B^2 and its cushioning cylinder A^2 .

What I claim as new and desire to secure by Letters Patent is:

1. In a pressure motor, the combination with two parallel, opposed cylinders, of a piston in each, a rod for each piston, a crosshead for each rod traveling on the opposite cylinder, and means for rigidly connecting said crossheads.

2. In a pressure motor, the combination with two parallel, opposed cylinders, one offset with respect to the other, of a piston in each, a rod for each piston, a crosshead for each rod traveling on the opposite cylinder, and means for connecting said crossheads.

3. In a pressure motor, the combination with two parallel, opposed cylinders, of a piston in each, a rod for each piston, a crosshead for each rod traveling on the opposite cylinder, and a connection between the two crossheads movable therewith.

4. In a pressure motor, the combination with two parallel, opposed cylinders open at their adjacent ends, of a piston in each, a rod for each piston, a crosshead for each rod traveling on the opposite cylinder, and a rod connection between said crossheads.

5. In a pressure motor, the combination with two parallel, opposed cylinders open at their adjacent ends, of a piston in each, a rod for each piston, a crosshead for each rod traveling on the opposite cylinder, a rod connecting the crossheads, and a control valve for alternately admitting pressure to the closed end of one cylinder while exhausting the closed end of the other.

6. In a pressure motor, the combination with two parallel and opposed cylinders, of a central support for their adjacent ends, a piston in each cylinder, a rod for each piston, a crosshead for each rod traveling on

- the opposite cylinder, and a connection between the two crossheads passing through the said central support.
7. In a pressure motor, the combination with two sets of parallel and opposed cylinders, each set comprising a plurality of cylinders, pistons in each cylinder, rods for each piston, a common crosshead for the piston rods of one set traveling on the cylinders of the opposite set, and means for causing said crossheads to move in unison.
8. In a pressure motor, the combination with two sets of parallel and opposed cylinders, each set containing a power cylinder and a cushioning cylinder, of pistons in each cylinder, rods for each piston, a crosshead for the rods of each set, and a connection between the two crossheads, whereby the cushioning cylinder in one set acts upon the power cylinder in the other set.
9. In a pressure motor, the combination with two sets of parallel and opposed cylinders offset with respect to each other, each set containing a power cylinder and a cushioning cylinder, of pistons for each cylinder, rods for each piston, a crosshead for the piston rods of one set traveling on the cylinders of the other set, and means for rigidly connecting said crossheads.
10. In a pressure motor, the combination with two parallel opposed cylinders of a piston in each, a rod for each piston, a crosshead for each rod traveling on the opposite cylinder, and an operating connection connected to one of said crossheads.
11. In a pressure motor, the combination with parallel and opposed cylinders open at their adjacent ends, of pistons, a rod for each piston, a crosshead for each rod traveling on the opposite cylinder, and a control valve for alternately admitting pressure to the closed end of one cylinder while exhausting the closed end of the other cylinder, and for interconnecting the ends of said cylinders to equalize the pressure therein.
12. In a pressure motor the combination with two single-acting cylinders opposed and offset with respect to each other, of a piston and piston rod in each cylinder, the piston rod of one cylinder overlapping in its travel the other cylinder, and a connection between the two piston rods whereby both may act upon the same load.
13. In a pressure motor the combination with two single acting power cylinders opposed and offset with respect to each other, of a piston and piston rod in each cylinder, the piston rod of one cylinder overlapping in its travel the other cylinder, means for guiding each piston rod externally and parallel to the opposite cylinder and a connection between the two rods whereby both may act upon the same load.
14. A pressure motor comprising a supporting standard having upper and lower sets of openings and a central guiding opening, power and cushioning cylinders arranged in pairs and having adjacent ends in said sets of openings, pistons and rods in the cylinders, a crosshead for each pair of cylinders and connecting the piston rods thereof, and a rod connecting the crossheads and slidably through the guiding opening.
- In witness whereof I have hereunto set my hand, before two subscribing witnesses, this 4th day of November, 1910.
